BUCKET TYPE MECHANICAL MOLE
Frank C. Peterson, Oroville, Calif., assignor to Amo
Placer Mines, Inc., Oroville, Calif., a corporation of
California

Filed Sept. 12, 1958, Ser. No. 760,804
6 Claims. (Cl. 262—5)

This invention relates to a digging device, and more particularly to a mechanical digging device using the crowd method for underground tunneling and digging.

Underground and tunnel digging is extremely costly and it is one of the purposes of this invention to provide substantially automatic digging equipment capable of operation by a maximum of two men which will reduce the digging cost per yard, and accomplish this objective without the necessity of bringing power to the machine, other than electricity.

Another object is to provide a mechanical mucking machine which may readily be moved into position and continue to be moved forwardly as the digging progresses by its own means, all without complicated rigging or other supplemental moving equipment.

Still another object is to provide a mechanical digging machine for digging into the face of a bank, which will dig tight material without blasting and its attendant hazards, while, at the same time, will automatically back off if an unexpected obstacle requiring power to dislodge beyond the setting of the automatic drive or thrust controls, is encountered.

Another object is to provide a machine which will dig a cut twenty feet wide and nine feet high from a single base location.

Another object is to provide a mechanical digger which can operate successfully and maintain volume operation in the confines of a six foot by six foot tunnel.

A further object is to provide a machine having a continuous bucket line for accomplishing the digging and delivery of the material to be removed in a relatively steady stream to a conveyor which makes possible the use of continuous belt conveyors, as no large volume of material is dumped at any one time.

It is a further object to provide a mechanical digging boom having a continuous bucket line, using hexagonal drive tumblers for operating the bucket line.

Another object of the invention is to provide a bucket line for such purposes with each bucket having an extended forward lip contiguous with the back thereof and digging teeth extending outwardly from the heel thereof which loosen the bank for the encounter of the bucket immediately following.

Still another object of the invention is to provide a digging machine which is completely self-contained, not only so far as operating the digging boom, but with respect to the forward movement of the device, itself.

A further object is to provide such a digging machine made for the most part with standard equipment and in which the operating drive unit may be removed as a unit for overhaul and repair without dismantling the entire machine.

A still further object of the invention is to provide a method of digging the face of a bank wherein there is no tendency or opportunity to push the material into the face of the bank and wherein the arc of travel of the bucket cutting lip is changed during the digging operation.

A still further object is to provide automatic controls for the entire digging and moving operations which can be handled by a single operator from one side of the machine only.

Further objects are to provide a construction of maximum simplicity, economy, and ease of manufacture, also

2

such further objects, advantages and capabilities as will fully appear and as are inherently possessed by the device and the invention described herein.

Invention further resides in the combination, construction and arrangement of parts illustrated in the accompanying drawings, and while there is shown therein a preferred embodiment thereof, it is to be understood that the same is merely illustrative of the invention and that the invention is capable of modification and change, and comprehends other details of construction without departing from the spirit thereof or the scope of the appended claims.

Referring to the drawings:

FIGURE 1 shows the mechanical mole of the present invention in side elevational view with the digging boom substantially in a horizontal position. The approximate maximum upward angle of digging and the approximate lower maximum angle of digging are indicated by the phantom broken lines, as well as the position of the maximum forward digging for any one base location of the machine;

FIGURE 2 is a top plan view of the mechanical digger shown in FIGURE 1 with the approximate maximum lateral angularity for the digger shown in broken phantom lines. The receiving trough at the rear end has been omitted in this view;

FIGURE 3 is a rear elevational view of the digger shown in FIGURE 1; and

FIGURE 4 is a schematic arrangement, showing the coupled operation of the manual hydraulic operating controls for the device.

Referring now more particularly to the drawings in which like reference characters have been used to designate like parts in the several views, it will be observed that the mechanical digger of the present invention is constructed upon a revolving table or tub which is generally designated by the numeral 10. The stationary portion comprises a stationary flat plate 11 having a peripheral upstanding flange 12. Immediately above, but out of contact with the top edge of the peripheral flange 12, is base plate 14 which is substantially coextensive with the plate 11. The base plate 14 is mounted concentrically on the stationary plate 11 by two cooperating means. At the center, a collar 15 secured to the under surface of the base plate fits over a stationary pivot pin 16 which is secured to the stationary plate 11 at the center thereof. Suitable bearings may be added in the collar 15 to secure easy rotation of the base plate 14 around the pivot 16 and to take some of the thrust. The other means comprises a plurality of rollers or heavy casters 17 which are mounted in any suitable manner on the under surface of the base plate 14 for rolling contact with the inner face of the plate 11. The rollers or casters 17 are mounted on plate 14 in such a manner that the peripheral flange 12 also acts as an outer guide or raceway for the said rollers or casters. For convenience of forward and rearward drag movement of the tub, a pair of skids 18 having suitable coupling openings 20 are provided. The skids 18 rest on the floor level 21 and provide clearance for the tub 10 as it is moved along the floor.

It is apparent that the tub 10 can be mounted on any suitable means of conveyance rather than the skids 18, such as tracks, wheels, rollers or track-laying treads. The use of any of these, however, may be limited by the space demands of the digging.

Mounted in parallel relationship on said base plate in planes perpendicular to the plate 14 and at either side of the longitudinal axis of the machine are side plates 22 forming a pedestal thereon. The side plates have a rear overhang portion 23 with parallel longitudinal slots 24. Mounted above and below the opening of each of said slots and on the outside thereof are angle members 25

which form slide guides at either side of the pedestal. The center of the slots 24 lies in the longitudinal, horizontal plane which represents the center line 26 of the boom assembly, which is generally designated 27, when the same is in the horizontal position. Mounted for horizontal sliding action within the groove and slide angle members 25 at each side are trunnion blocks 28 in which are journaled the horizontal, transverse driven shaft 39. As shown in FIGURE 1, the shaft 30 also acts as the pivot mounting for the vertical raising and lowering of the boom assembly 27.

The boom which is generally designated as 27 is somewhat cigar shaped, closed by vertical side walls 31 and by a top 32. The boom housing encloses the driving mechanism which comprises an electric gear motor 33 connected to a standard Ford truck transmission 34, which in turn rotates drive shaft 35 journaled as at 36 in either side of the housing 31, to drive gears 37 located just outside of the housing. It is to be understood, of course, that there are hinged openings (not shown) in the side walls of the boom housing 31 providing easy access both to the motor 33 and to the transmission 34, which are bolted within the framework of the boom and therefore protected at all times. It follows, therefore, that either the motor or the transmission may be uncoupled, unbolted and removed without dismantling the remainder of the equipment. The boom housing and therefore the entire boom assembly 27 at the rear end thereof is mounted for pivotal movement about the shaft 30. Suitable thrust bearings 38 are provided for this purpose. It is therefore apparent that all vertical movement of the boom assembly 27 has the shaft 30 as its pivot point. Mounted on shaft 30 in line with drive sprockets 37 are a pair of driven sprockets 40. The sprockets 37 and 40 at either side are connected by roller chains 41 which obviously drive simultaneously at the same rate. Also mounted on shaft 30 and driven thereby are a pair of hexagonal tumblers 42. At the beginning of each alternate face of the hexagonal tumbler 42 is a projecting point or tooth 43, the purpose of which will be explained subsequently. Carried at the forward end of the boom frame 26 is an idler shaft 44 suitably journaled at either side as at 45. Mounted on the idler shaft 44 at either side of the boom is a pair of hexagonal tumblers 46 identical with those at the rear with projecting teeth at the beginning of each alternate perimeter face. Extending around the hexagonal tumblers 42 and 46 at either side is an endless chain 47 which is the bucket chain. The bucket chain is composed of alternate solid and double links having a distance between the connecting links such that in making the turns at either end the links will fit flush along the peripheral faces of the hexagonal tumblers. The bucket chains are driven in a counterclockwise direction as viewed in FIGURE 1, by means of the hexagonal tumblers 42. This is accomplished by the contact of the projecting points or teeth 43 engaging in the heels of the solid links with the double links straddling the projecting points or teeth 43. In this manner and at both ends of the bucket line are always in positive engagement and control of the hexagonal tumblers. A plurality of buckets 48 is carried by the chain.

While the buckets 48 have the conventional and usual shape of drag line buckets, nevertheless there are several important features which distinguish this type of bucket line from others previously known. In the first place they are secured to the chain at one point only so that they are free to move along the straight travels and pivot in making the angular turns at either end. They are hinged to the solid links of the chain 47 by means of the pins which join the links on a line with the digging lip thereof as at 50. At the end of the boom, in making the turn on the hexagonal tumblers 42 and 46, but with particular reference to the digging end and tumbler 46, the buckets move upwardly in other than a circular path. This permits the digging lip of the buckets 48 to engage

the digging face on a relatively flat curve to fill the bucket. When the bucket is filled and as it passes the longitudinal axis of the boom, the bottom of the bucket swings free of the chain 47 and the digging lip is withdrawn in a relatively flat curve in a rearwardly direction. The buckets are arranged closely together and each bucket has a flat back 51 and an elongated forward lip 52 integral therewith. Near the base of each bucket on the exterior thereof are a pair of digging teeth 53, which, after the bucket has passed the digging face and been filled, engages the digging face and loosens the material for the next bucket. As the bottom of the filled bucket 48 swings clear of the chain 47 on its delivery passage, the digging teeth 53 engage the digging face with substantial power and force to make the loosening most effective. In digging very tight material the digging teeth 53 are removed from the base of the bucket and placed along the digging lip of the bucket.

Since the boom assembly 27 is supported in the frame of the machine only by the pivot shaft 30 at the rear, it is apparent that the boom would fall down at the front thereof unless there was some support. At either side of the boom housing 31 are laterally extending wings 54 which extend upwardly at a slight angle. From the outer ends of these wings 54 the crowd or lateral support hydraulic cylinders 56 are suspended by a universal connecting joint 55. At the other extremity of the hydraulic cylinders 56 extends the piston stem 57 to which is secured a foot 58. The feet 58 are cup-shaped and are hard faced around the edges so that they will dig into the floor 21. The manner of supporting the boom assembly 27 is clearly shown in FIGURE 3. Because of the universal joint 55 and the foot 58, the lateral support or crowd cylinders 56 may be independently placed in any desired angle or position to support the boom in any adjusted position vertically or laterally or any combination thereof. It is obvious that in so doing the boom assembly should not be subjected to any twist.

Along the under surface of the boom at either side and in contact with the travel of the chains 47 are digging shoes 60 to force the buckets to dig without contacting the boom housing. On the top surface at the forward end are carrying shoes 61 to support the loaded buckets and to keep them from engaging the upper surface of the housing.

Also secured to the outer ends of the forward wings 54 are lateral attaching brackets, the piston stem 63 of the vertical lift cylinders 64 are pivotally attached to the bracket 62 by means of pivot ends 65. A bracket 66, which is firmly secured to the base plate 14, pivotally mounts the lower end of the vertical lift cylinders 64. It will be readily observed that by raising or lowering the piston rods 63, the boom assembly 27 may be raised or lowered to any adjusted position within the limits of the device. Because of the forces applied to the outer ends of the wings 54 it has been deemed advisable to provide a tie brace 67 connecting the two extremities. Obviously the tie brace 67 is arched so there will be no interference with the buckets passing beneath it.

It has been found advisable, particularly with respect to the forward hexagonal tumblers 46, to cover them with removable protective circular covers 68, which, of course, do not interfere in any way with the operation of the boom or the buckets and do not move.

Fitted longitudinally between the slides at each end of the side plates 22 and secured to the side plates is a pair of hydraulic cylinders 70, one at either side. The piston stem 71 for these cylinders is secured to the block 28. It is apparent that since the shaft 30 is movable longitudinally in the slots 24 and slide guides 25 by means of its mounting blocks 28, the entire boom may be moved forwardly and rearwardly within the limits of the stroke of the piston 71. Thus, the boom assembly 27 can be moved forwardly without moving the entire machine itself and can dig a substantial amount without being

stopped for movement of the entire machine to another forward position. Although the pressure in cylinders 70 is the same as that applied to any other cylinder in the system, nevertheless it is set and controlled at a lesser pressure by the setting of the relief valve mechanism 72. Thus, the machine can only dig up to the predetermined pressure setting of the cylinder and no more. Accordingly, in the digging operation, if the bucket line encounters an object requiring a force greater than the drive or thrust of the setting, the boom will automatically back off due to release of fluid pressure in the cylinders 70 and when this object is passed, the pressure is restored to the cylinders and the boom moves forward again. In this manner the digging force of the boom and twin bucket line is not jeopardized and damage to the machine is minimized.

Mounted at either side on the side plates 22 forming the pedestal are upwardly directed hydraulic cylinders 73 with their piston stems 74 pivotally connected to an overhead cross brace 75. At the central portion of the cross brace 75 is a pad 76 for bearing against the ceiling of a tunnel. The pad 76 may be rotatably mounted to provide for rotation of the machine without releasing the bearing pressure on the ceiling. In order to secure better anchoring of the machine to the ceiling of the tunnel and thereby promote better digging performance, are a pair of bar members 77 angularly disposed and pivoted at one end to the cross brace 75 and at the other end to the upper overhang portion of the side plates 23. The support of the bar members 77 minimize the likelihood of bending the stems 74.

At the rear or discharge end of the chain bucket line is a receiving trough 78 which has inwardly sloping sides 80, the bottom of the trough being an endless belt conveyor 81 driven by a separate motor 82. The motor 82 and the drive pulley 83 for the belt conveyor 81, as well as the receiving trough 78, are mounted between the side plates 22 on the base plate 14 for rotative movement therewith. To maintain this position and for reinforcement accommodating the weight of the material delivered to the belt conveyor 81, rigid side brackets 84 are secured to the receiving trough 78 at either side and are anchored at the top thereof to the lower portion of the side plate overhangs 23 of the pedestal. The delivery end of the receiving trough 78 must necessarily always be in position with respect to the receiving end of the normal belt conveyor 85. For this purpose a pivotal coupling has been devised which will maintain this relative position regardless of the digging position of the machine. Since the delivery end of the belt conveyor in the trough 78 must overlay the receiving belt 86 of the normal conveyor 85, a bracket 87 is secured to the under portion of the receiving trough 78. To this bracket 87 is secured an outwardly projecting face plate 88 having an aperture therethrough. To the under support 90 for the normal belt conveyor 85 is secured a pivot pin 91 which projects through a face plate 92 also secured to said bracket 90. The pivot pin 91 projects through the aperture of the face plate 88, bringing the two face plates 92 and 88 into contact with a substantial supporting surface in contact and providing a pivotal mounting. In this manner the delivery end of the receiving conveyor 78 is always maintained in appropriate position with the normal conveyor 85.

Referring now to FIGURE 4 and particularly to the diagrammatic showing therein, a typical flow control diagram is shown for the operation of the hydraulic cylinders in the operation of valve 104. However, FIGURE 4 has specific reference to the necessary simultaneous operation of valves 104 and 105. In order to allocate or orient the controls for the machine, it is to be noted that the controls are all on the right side of the machine so that a single operator manipulating the control valves can control all of the movements of the device. The hydraulic controls are valves generally designated 100.

Referring to FIGURE 1, valve 101 controls the simultaneous operation of cylinders 70 and moves the boom assembly 27 forwardly and rearwardly. Valve 102 controls the simultaneous operation of cylinders 64 for raising and lowering the boom assembly. Valve 103 controls the simultaneous operation of the cylinders 73 for anchoring the machine against the ceiling. Valves 104 and 105 must be operated conjointly and control the movement of the anchoring cylinders 56. Each of the control valves 100 is a dual acting valve which has a central neutral position and is moved away from the operator for one direction and toward the operator for the reverse direction. Valves 101, 102 and 103 may be operated independently, but valves 104 and 105 must be operated in conjunction with each other and can be moved forward together or rearwardly together or in opposite directions together. This flexibility is of course required because of the varying conditions which are frequently encountered in positioning the anchoring feet 58. This means that either cylinder may be reversed, i.e., the piston in one cylinder can be pushing downwardly while the other is being released and moved upwardly, or both can go in the same direction at the same time or either can be stationary while the other moves. To obtain this action the valves 104 and 105 are arranged in parallel with a double ball check valve 106 between them. As diagrammatically shown in FIGURE 5, when the valves are in the neutral position, liquid in the feed line 107 passes through valve 104 and out to the discharge line to the reservoir 108. If, for example, the valve 104 is opened to put pressure in the cylinder 56 and extend the piston stem 57, the incoming liquid in line 107 would be fed to the line 110 to the pressure side of the cylinder 56. At the same time liquid would be delivered to the double ball check valve 106 and liquid would flow into the valve 105. If the valve 105 were in the neutral position the liquid would flow through the valve into the discharge line 108 to the reservoir. However, if both valves were opened simultaneously to the pressure side of their respective cylinders 56, then liquid would be delivered to line 110' to the pressure side of its cylinder 56. Of course the opposite is true. If valve 104 is moved to reverse the direction or rearwardly, then fluid pressure is delivered to the line 111 and at the same time to the opposite side of the double ball check valve 106, to the valve 105. If the valve in 105 is moved in the same direction, then fluid is delivered to the line 111'. Since fluid pressure is fed to valve 105 through valve 104, to operate valve 105 alone it is necessary to hold valve 104 in a pinched position in either direction. This means that valve 104 is opened sufficiently to permit fluid to pass therethrough to valve 105, but not sufficient to operate cylinder 56 through lines 110 or 111. This maneuver is needed in retracting the foot 58, and is used only at a time when there is no load on the foot.

In this manner a single operator controls the entire digging operation and movement of the machine. However, he does require a helper on the opposite side to assist with the placing and anchoring of the foot 58 and cylinder 56 on that side and to appraise him of the extent of the movement permissible for the boom on the opposite side to him.

In order to prevent any canting in the raising and lowering of the boom assembly 27 and to assist in minimizing any canting or twist during the digging operation, the side plates of the boom 31, just ahead of the axis of rotation of the base, are provided with rollers which roll against the inner faces of the side plates 22 forming the pedestal of the machine. These rollers not only provide a smooth vertical movement, but prevent the likelihood of twisting or canting of the boom in the pedestal, resulting in twisting and binding of the shaft 30.

It is to be understood that the device carries its own liquid reservoir and pressure system, including a motor and pump for handling the fluid pressure systems. Since

this is all conventional equipment it is not shown. However, these are preferably located on the side opposite to the controls as there is more room for the mounting and more protection for the equipment.

Also mounted on and secured to the base plate 14 are upstanding circular skirts 95. These skirts 95 serve as protection for the operator at one side and for the helper at the opposite side of the machine against any inadvertence in contacting any part of the machine. The skirts do not extend forwardly or rearwardly enough to interfere with the movement of the boom assembly 27, nor high enough to prevent easy operation of the control valves 100.

Operation

The operation of the device is really quite simple. The digging machine is moved up to the digging face with the boom assembly in substantially horizontal position and with the boom itself in the most rearwardly position accomplished by cylinders 70. If it is a tunnel operation, then the machine would be approximately in the middle of the center of the tunnel floor so as to take advantage of the maximum lateral movement of the boom. Having thus positioned the machine the operator then pulls valve 103 toward him, raising the overhead cross brace 75 until the pad 76 is firmly positioned against the ceiling of the tunnel. In this manner there is a downward pressure on the base of the machine. At the same time, by means of angular bar members 77 the rear overhang portion 23 of the side plates 22 forming the pedestal on the base are firmly positioned and steadied. These bar members 77 also function to prevent any bending of the piston stems 74. When the proper holding position of the ceiling brace and pad 76 is assumed the valve 103 is moved to neutral position, maintaining the fluid pressure to accomplish the holding. Next valve 102 is pushed away from the operator to remove liquid from the cylinders 64 so that the stems 63 are retracted within the cylinders, lowering the boom assembly to its lowermost digging position which is substantially that shown in FIGURE 1 as position L. It is apparent that the lowermost position will dig to the floor level 21 and that the position L of the drawings is not quite the maximum position. The valve 102 is then moved to the neutral position so that the boom is maintained in this position. Valves 104 and 105 are then operated and manipulated to first extend the stems 57 until one of them reaches the floor level. For the purpose of this discussion we will assume, for example, that the stem on the side of the helper is moved so that the foot 58 engages the floor 21. Accordingly, by continuing the extension of this stem, the entire base plate pedestal and boom assembly are rotated on the pivot 16 laterally to the position M shown in FIGURE 2. The pad 76 of the ceiling anchor is axially aligned with the pin 16 and is so arranged as to permit this rotation without release of the pressure. The machine is then ready for the digging operation and the starter switch is pressed to operate the motor 33, driving the transmission 34 and operating the twin chain bucket line comprising chains 47 and the buckets 48. As viewed from the operator's side shown in FIGURE 1, the chain bucket line travels counterclockwise so that the front edge of the buckets approach the bank, cut into the same, load, and then transport the removed material rearwardly where it is dumped into the receiving trough 78 and from thence onto the standard conveyor belt 85. It will be observed that as the empty buckets 48 approach the digging end, the chain moves upwardly at a slight angle with the chain being held taut by the digging shoes 60. As the chain is picked up by the hexagonal tumblers 46, the bucket being attached to the chain only at a single point 50 will travel upwardly and outwardly to the maximum point where the meeting corner of the hexagon beneath the front edge of the cup is on the longitudinal center line of the boom. From this point on, the bucket lip is withdrawn and the arc of the lip

proceeds in a gradually reducing diameter until it leaves the influence of the hexagonal tumblers 46. Accordingly, by using the hexagonal tumblers which change the arc of the travel of the bucket line at each end, the arc of the bucket digging lip also changes so that after it passes the center line the bucket pulls away from the bank to shear the material rather than pull upwardly against the ceiling. It thus follows that the bucket in digging travels in a wider arc until a point is reached which corresponds with the filling of each bucket, after which the filled bucket moves from the digging face in a substantially reduced and different arc caused by the falling of each bucket back upon its flat back 51 after passing the longitudinal center line of the boom, as shown in FIGURE 1. If ordinary sprockets were used, the digging motion would tend to push the rock into the bank or the face which, of course, cannot be done successfully. The changing of the arc accomplished by the present device is a great advantage, particularly in the digging of tight material. As before described, also, the heel of the buckets 48 carry a pair of digging teeth 53 which come into operation against the cutting face after the bucket has passed over and above the horizontal center line of the boom. These teeth dig into the face of the bank, loosening the material in preparation for the cutting and loading of the following bucket.

As has been before described, the back of each bucket has an integral forwardly extended lip 52 which reaches almost up to the bucket immediately ahead. This extended lip performs two important functions, one is it acts as a spill carrier for the rearward transportation of the loaded buckets. As can be seen in FIGURE 1, the loaded bucket is turned on its back and carried rearwardly, spilling some of the contents onto the lip 52 which otherwise would be spilled onto the top of the boom, unnecessarily loading the same and fouling the twin chains. The other function of the lip occurs at the discharge end. Here the lip is long enough to provide a chute and prevent spilling of the contents of the bucket until the lower bucket is completely out of the way. As the machine is operated and digs into the face of the bank, the operator gradually moves the boom assembly upwardly in a vertical arc by operating valve 102 and moving it outwardly. The boom is moved gradually in a vertical arc until it reaches its maximum digging height which is substantially the position shown in FIGURE 1 as N. The boom is then rotated on its base to the next position where the same procedure is repeated and this occurs in increments along the digging face until the digging has been completed to the maximum distance to the left-hand side or the position shown as P in FIGURE 2. Then the same procedures are repeated by operating the valve 101 to move the boom forward by increments until the maximum forward distance indicated by the broken line position Q in FIGURE 1 has been attained. Since the maximum digging for the original face position has been accomplished by all of these maneuvers of digging from position L to position N in all of the horizontal increments from M to P and all the vertical increments from the minimum setting of the boom to the maximum reach Q, it is now necessary to move the entire base 10 forward, which moves the position of the entire machine, and repeat the same procedures.

The device illustrated in FIGURE 1 can be moved forwardly under its own power by releasing the ceiling stabilizer contact and withdrawing the stems 74 of the cylinders 73, releasing the anchorage of the cylinders 56 and swinging these into a rearward position and using them as walking cylinders. By doing this several times the device may be advanced forwardly the required distance to the proper operating contact with the face of the bank.

Obviously, if space permits, the base 10 may be mounted on wheels or rollers with or without tracks or on a track laying tractor and moved again under its own

power. These, however, are only obvious ways of accomplishing the nondigging, forward movement of the entire machine and are only possible where space permits.

It is to be understood that as the various digging procedures are followed, the receiving chute 78 attached at the rear end of the pedestal and movable therewith, follows the horizontal rotating position, but swings oppositely to that of the digging end of the boom. Since the loading end of the conveyor belt 85 is supported by the bracket 87 and lip 88, this end swings to accommodate the position of the receiving conveyor 78 so that they are always in line. It is not necessary to uncouple the pivot 90 as the boom moves from retracted position to its extended position Q, because the bracket 87 is mounted in a slot or guide in the bottom of the receiving conveyor 78.

I claim:

1. A mechanical mole of the type described comprising in combination a base, a horizontally pivoting pedestal on said base, a boom mounted at one end for slideable movement in a horizontal plane on said pedestal rearwardly of the vertical axis thereof for movement therewith in a horizontal plane and pivotally mounted in said sliding mounting for separate movement in a vertical arc, a continuous chain and bucket line traveling on the upper and lower faces of said boom, said buckets being hingedly mounted on said chain each adjacent the lip thereof, to swing away from the chain in other than a circular path at each end of the boom, said buckets having a forwardly extending elongated flat lip integral with the back thereof and digging means externally mounted adjacent the trailing edge for loosening the digging face for the next succeeding bucket, hexagonal tumblers mounted at each end of said boom for driving said chain and bucket line and cooperating with said bucket mounting for varying the arc of the bucket travel at the turns, said tumblers having beginning triangular points projecting from alternate peripheral faces for engaging the pivot pins between the double links of said chain, hydraulic means mounted on said base at either side of said boom to simultaneously adjustably raise or lower said boom and chain bucket line in a vertical arc and hold the same in the adjusted position, power means mounted within said boom and connected to at least one of said tumblers for driving said chain and bucket line and control means for separately moving the boom and bucket line forwardly in said slideable mounting to keep the buckets in contact with the digging face, within the limits of the slideable mounting.

2. A mechanical mole for underground digging comprising in combination a base, hydraulic means supported on the base for adjustably and pivotally anchoring the machine to the ceiling, a horizontally pivoting pedestal on said base, a boom mounted at one end for slideable movement in a horizontal plane on said pedestal rearwardly of the vertical axis thereof for movement therewith in a horizontal plane and pivotally mounted at its rear portion in said sliding mounting for separate movement in a vertical arc, a continuous twin roller chain bucket line traveling on the upper and lower faces of said boom, said buckets being hingedly mounted on said chain each adjacent the lip thereof, to swing away from the chain in other than a circular path at each end of the boom, said buckets having a forwardly extending elongated flat lip integral with the back thereof and digging means externally mounted adjacent the trailing edge for loosening the digging face for the next succeeding bucket, hexagonal tumblers mounted at each end of said boom for driving said chain bucket line and cooperating with said bucket mounting for varying the arc of the bucket travel at the turn, said tumblers having beginning triangular points projecting from alternate peripheral faces for engaging the pivot pins between the double links of said chain, hydraulic means mounted on said base at either side of said boom to simultaneously adjustably raise or

lower said boom and chain bucket line in a vertical arc and hold the same in the adjusted position, hydraulic means for rotating said pedestal to move said boom and chain bucket line horizontally in the adjusted position, and

5 power means mounted within said boom and connected to one of said tumblers for driving said chain bucket line, and means for separately moving the boom and bucket line forwardly from the adjusted position in the slideable mounting to keep the buckets in contact with the digging face, within the limits of the slideable mounting.

3. A mechanical mole of the type described comprising in combination a base, a horizontally pivoting pedestal on said base, a boom mounted at one end for slideable movement in a horizontal plane on said pedestal rearwardly of the vertical axis thereof for movement therewith in a horizontal plane and pivotally mounted at its rearward portion in slideable mounting for separate movement in a vertical arc, a continuous twin roller chain bucket line traveling over the upper and lower faces of said boom,

20 said buckets being hingedly mounted on said chain each adjacent the lip thereof, hexagonal tumblers mounted at each end of said boom for driving said chain bucket line and cooperating with said bucket mounting for varying the arc of the bucket travel at the turn, said tumblers having beginning triangular points projecting from alternate peripheral faces for engaging the pivot pins between the double links of said chain, hydraulic means mounted on said base at either side of said boom to simultaneously

25 adjustably raise or lower said boom and chain bucket line in a vertical arc and hold the same in the adjusted position, power means spaced from either side of said boom secured thereto in the plane forward of the center line of horizontal rotation for rotating said pedestal boom and chain bucket line horizontally and anchoring the same in the adjusted position either vertically, laterally, or any combination thereof, power means mounted on

30 said base at either side of said boom to simultaneously adjustably raise or lower said boom and chain bucket line in a vertical arc and hold the same in the adjusted position, power means mounted within said boom and connected to one of said tumblers for driving said chain bucket line, and means for separately moving the boom and bucket line forwardly from the adjusted position in the slideable mounting to keep the buckets in contact with the digging face, within the limits of the slideable mounting.

4. A mechanical mole for underground digging which

45 can be self-propelled to the digging face, comprising in combination a base, hydraulic means supported on said base and movable therewith for adjustably and pivotally anchoring the machine to the ceiling, a pedestal mounted on said base for pivotal movement in a horizontal plane

50 the axis of which is in line with said ceiling anchoring, a boom mounted at one end for slideable movement in a horizontal plane on said pedestal rearwardly of said axis for horizontal rotation therewith and pivotally mounted at the rearward portion in said slideable mounting for independent movement in a vertical arc,

55 a continuous twin roller chain bucket line traveling along the upper and lower faces of said boom, said buckets being hingedly mounted on said chain each adjacent the lip thereof, hexagonal tumblers mounted at each end of said boom for driving said chain bucket line and operating with said bucket mounting for varying the arc of the buckets travel at the turns, said tumblers having beginning points projecting from alternate peripheral faces for engaging the pins between the double links of said chain, hydraulic means mounted on said base at either

60 side acting simultaneously for raising and lowering the said boom on its pivotal mounting in a vertical arc, hydraulic ram means spaced from either side of said boom secured thereto forwardly of the axis of rotation of said

65 pedestal for horizontal movement of said pedestal boom and chain bucket line and for anchoring the same in the adjusted position either vertically, laterally, or any combination thereof, power means mounted within the boom and connected to one of said tumblers for driving said

70 chain and bucket line, and means for separately moving

the boom and bucket line forwardly from the adjusted position in the slideable mounting to keep the buckets in contact with the digging face while in the adjusted position, within the limits of said slideable mounting.

5. A mechanical mole for underground digging comprising in combination a base which is moved by its own power to the digging face, hydraulic means supported on said base and movable therewith for adjustably and pivotally anchoring the machine to the ceiling, a pedestal mounted on said base for pivotal movement in a horizontal plane the vertical axis of which is in line with said ceiling anchoring, a boom mounted at the rear end thereof for slideable movement in a horizontal plane on said pedestal rearwardly of said axis for horizontal rotation therewith and pivotally mounted at the rear end thereof in said slideable mounting for independent movement in a vertical arc, a continuous twin roller chain bucket line traveling along the upper and lower faces of said boom, said buckets being hingedly mounted on said chain each adjacent the lip thereof, hexagonal tumblers mounted at each end of said boom for driving said chain bucket line and cooperating with said bucket mounting for varying the arc of the bucket travel at the turns, said tumblers having beginning points projecting from alternate peripheral faces for engaging the pins between the double links of said chains, hydraulic means mounted on said base at either side acting simultaneously for raising and lowering the boom and chain bucket line in a vertical arc on its pivotal mounting, hydraulic means for limited horizontal forward and rearward movement of said boom and chain bucket line in said slideable mounting independently of said pedestal, hydraulic ram means spaced from either side of said boom secured thereto forward of the axis of rotation of said base for rotating the pedestal, boom and chain bucket line laterally and anchoring the same in the adjusted position either vertically, laterally, or any combination thereof, valve systems for controlling, adjusting and holding the setting of the various hydraulic means each independently of the other, and power means mounted within the boom and connected to one of said tumblers for driving said chain bucket line.

6. A mechanical mole for underground digging comprising in combination a self-propelled base, hydraulic means supported on said base for adjustably and pivotally anchoring the machine to the ceiling when in position, a pedestal mounted on said base for pivotal movement in a horizontal plane the vertical axis of which is in line with said ceiling anchoring, a boom mounted at the rear
